UNITED STATES PATENT OFFICE.

HERMAN R. WILLIS AND REUBEN M. WILLIS, OF CHANUTE, KANSAS.

OIL-WELL PUMP JACK.

Application filed July 30, 1920. Serial No. 399,976.

To all whom it may concern:

Be it known that we, HERMAN R. WILLIS and REUBEN M. WILLIS, citizens of the United States, residing at Chanute, in the 5 county of Neosho and State of Kansas, have invented certain new and useful Improvements in Oil-Well Pump Jacks, of which the following is a specification.

The present invention relates to pump 10 jacks for oil wells and has for its principal object to provide an improved device of this character which can be readily applied to or detached from a well and which involves but few parts in its simply designed 15 construction.

A further object is to provide a pump jack having the oscillating beam mounted for quick and easy movement without binding or side pull and so proportioned at the 20 hinges and joints as to avoid any possibility of the pump rod being forced forward or backward.

With the above and other objects in view, the invention may be said to reside in the 25 details of construction, combination and arrangement of parts as will be hereinafter more fully pointed out, reference being had to the accompanying drawings, wherein—

Figure 1 discloses the manner of attaching the improved jack to a well.

Figure 2 is a vertical sectional view taken on the line 2—2 of Figure 1, looking in the direction indicated by the arrow.

Figure 3 is a detailed view of the pump 35 rod gripping end of the beam, and

Figure 4 is a detailed view of the pump rod guide or cap plate which is fastened to the end of the beam.

In the drawings, 1 indicates the head end 40 of a well casing from which projects the tubing 2 and pump rod 3. The pump jack is designed to be attached to the head of the well casing and operates to raise the pump rod 3; the weight of the latter tending 45 to lower it as the beam of the jack is moved downwardly. In the present instance, the invention is connected to the head of the well casing 1 by means of a collar clamp iron 4 which is adapted to embrace the head of 50 the casing, being usually made of sections bolted together firmly so as not to slip out of place. This clamp is provided on opposite sides with outwardly directed studs 5 forming pivots for the fulcrum or oscillating arms 6 and 7 respectively. These arms 55 have their outer ends pivoted on opposite

sides to elongated lift beams 8. This beam is usually of heavy material and is made solid throughout the major portion of its length to add to its stability. One end however of this beam is bifurcated or slit longitudinally from edge to edge to provide side strips or tongues 9 and 10. These tongues are designed to be sprung apart to widen the space therebetween and have their top 60 edges incurved to suitably receive a corresponding curved cap plate 11. This cap plate is provided with a suitable number of openings whereby it may be conveniently fastened to the incurved edges of the tongues 65 9 and 10, thus holding them in sprung apart, spaced, relation and spanning over the space between them to provide a guide for the pump rod 3, the latter passing through and working conveniently in the 70 elongated slot 12 of the guide. The pump rod is thus passed between the split end of the lift beam and permits the beam to slide along the rod in the operation of the device. The beam is provided with a suitable brace 75 to insure strength and to reinforce the beam in case of a heavy lift or strain, as when used on a very deep well, and this brace comprises a rod 13 having its respective ends fastened to the solid portions of the 80 beam, as indicated at 14 and 15 and supported intermediate its ends by a center block 16.

Designed for riding movement over the well clamp 4 is a beam which straddles the 85 well casing so that its side bars 17 and 18 fit in between the casing and the oscillating arms 6 and 7, resting upon the collar 1. Each side bar of the pull beam carries adjacent its opposite end a pair of curved brackets 90 19. Two of these brackets, adjacent one end are adapted to be bent inwardly toward each other to provide a single, projecting stud 20, perforated with an eye 21 to receive the connecting end of a turn 100 buckle coupling 22, the opposite end of which is designed to be connected to any suitable operating means for drawing the pull beam back and forth across the bearing clamp 4, thus rocking the beam 8 and moving the pump rod up and down. The remaining two brackets, at the opposite end of the pull beam, straddle the lower end of the oscillating beam 8 to support it on opposite sides, being pivoted thereto as indicated at 23; the brackets being curved downwardly so that the pivot is in direct line 105 110

with eye 21 of the opposite brackets and the center pivot 5 causing the pull to be in a less distance straight line without any tendency to draw the beam 6 forward or back but to lift it straight up and down. To insure ease of movement the parts are so proportioned that the guide 9 and pivot 23 of the beam are an equal distance from pivot 24, while the pivot 5 of the oscillating arm is the same distance from pivot 24 as both the pivot 23 and the guide 9. By reason of the curved brackets 19, the eye 21, pivot 5 and pivot 23 are in straight alignment so that the direction of pull is through the center of pivot 5.

From the foregoing it may be seen that a jack constructed along the principle of this invention embodies but a few, simple, easy operating parts, requiring but a small amount of material in their construction and so arranged and combined as to adequately and conveniently operate without binding or side pull. It is tensioned where the heaviest pull comes and easily attached to any well, there being only one or two fasteners to loosen when preparing to pull the rod to clean the well. Various changes in the details of construction, selection of material, etc., may be resorted to provided such contemplated changes, etc., properly fall within the scope of the invention as defined in the appended claim.

15 The device is attached to the well by means of the clamp 4 which clamps onto the casing head so as to support the side bars of the pull beam. The pump rod is then engaged with the head of the working beam, the latter passing up through the guide plate 11 in the manner previously described. A clamp 25 of any conventional form can be fastened to the pump rod, above the plate and provides an abutment for contact with the plate as the beam tilts upwardly for raising the pump rod. The tilting of the beam is of course accomplished by the reciprocating of the pull member back and forth across the clamp 4 which is done through means of the turn buckle 22, attached to some suitable source of power. As the pull member is reciprocated it pulls upon the lower or pivoted end 23 of the beam, causing it to rock on pivot 24 so that 30 the guide 11 is brought into abutment with the clamp 25, forcing the pump rod upwardly, the curvature of the plate affording an easy riding surface for the clamp as the jack is operated. The reciprocation of the pull member and the rocking of the beam 8 causes the arms 6 and 7 to oscillate on their pivots 5 as the pump rod is raised higher and higher so that when the pull beam has been drawn to the end of its forward stroke, the oscillating arms and beam will be approximately in vertically disposed relation, almost parallel with the pump rod and well casing. The stroke of the pump rod can be regulated by screwing up the 45 turn buckle or letting out the same, as the farther up the screw buckle is turned or

Having thus fully described our invention what we claim as new and desire to secure by Letters Patent is:—

A pumping jack comprising a collar clamp adapted to embrace the head of a well casing, oscillating arms pivotally connected at one end to said collar clamp, a lift beam pivotally attached to the opposite ends of said arms, said lift beam being slit longitudinally at one end to provide resilient 85 tongues, an apertured plate secured to the top of said tongues for maintaining the same sprung apart and also constituting a guide for a pump rod passing through the slit portion of the beam, parallel side bars, 90 connected to the opposite end of the lift beam and slideable over the collar clamp and connecting means at the front end of the slideable bars for actuating the lift beam and pump rod.

In testimony whereof we affix our signatures in presence of two witnesses.

HERMAN R. WILLIS.
REUBEN M. WILLIS.
